(57) **CLAIM**

The ornamental design for glowing speaker, as shown and described.

DESCRIPTION

FIG. 1 is top front right isometric view showing the glowing speaker of the invention.

FIG. 2 is a top rear right isometric view showing the glowing speaker of FIG. 1.

FIG. 3 is a front view showing the glowing speaker of FIG. 1.

FIG. 4 is a left side showing the glowing speaker of FIG. 1.

FIG. 5 is a right side view showing the glowing speaker of FIG. 1.

FIG. 6 is a top view showing the glowing speaker of FIG. 1.

FIG. 7 is a bottom view showing the glowing speaker of FIG. 1; and,

FIG. 8 is a rear view showing the glowing speaker of FIG. 1. Features shown in broken dashed lines are not claimed and form no part of the invention.
